CHAIN GRATE STOKER

William Lloyd, New York, N. Y., assignor to Combustion Engineering Company, Inc., New York, N. Y.

Original application May 5, 1939, Serial No. 271,859. Divided and this application October 31, 1939, Serial No. 302,231.

2 Claims. (Cl. 110—40)

The present invention relates to stokers and particularly to improvements in chain grate stokers.

In such stokers the grate is in the form of an endless conveyor made up of grate links arranged in side by side relation with narrow air spaces between the links, the latter being interconnected to form an endless conveying surface. The grate is driven from sprockets at the front 10 of the stoker and extends over idler sprockets at the rear.

A feature of the invention resides in a construction of chain grate which permits removal of a number of grate links in order to afford 15 access to parts beneath the grate without requiring the employment of apparatus to hold those portions of the grate between which a section has been removed.

The invention will be best understood upon 20 consideration of the following detailed description and the appended claims when read in conjunction with accompanying drawings in which:

Fig. 1 is a fragmentary view partly in section taken transversely of a chain grate embodying 25 the present invention and shows the improved means for interconnecting and driving the grate links.

Fig. 2 is a view on the line 2—2 in Fig. 1.

Figs. 3, 4, 5, and 6 illustrate modifications 30 of the improved means for interconnecting and driving the grate links to form the endless grate.

Fig. 7 is a sectional view on the line 7—7 in Fig. 4.

Fig. 8 is a sectional view through the grate, 35 looking downwardly as indicated by the section line 8—8, in Fig. 1, and shows the manner in which the rest of the grate remains connected together upon removal of some of the grate links to afford access to parts of the stoker beneath 40 the grate.

Fig. 9 is a view similar to Fig. 8 showing how the grate remains connected when drive links constructed as illustrated in Figs. 4 and 7 are employed.

45 Referring to the drawings, driving sprockets 10 at the front of the stoker and idler sprockets (not shown) at the rear are provided for advancing the fuel supporting surface of the grate towards the rear to feed fuel through the furnace.

50 The grate is in the form of an endless, belt-like conveyor made up of a plurality of rectangular grate links 13 disposed with their longitudinal axes in the direction of grate movement, the links being connected to each other and to chains 55 of driving links located at points spaced transversely of the grate as described hereafter. The grate links are arranged in end to end and side by side relation with air spaces between the ends and sides of adjacent links. As illustrated 60 in Figs. 8 and 9 the links of adjacent lines are

also staggered with respect to each other although this relation is not essential.

The grate links 13 are formed with transverse apertures 33 near each end. With the links in staggered relation apertures at opposite ends of adjacent links are in alignment so that rods 32 may be passed therethrough to interconnect the links, a transverse row made up of laterally aligned links being mounted on a pair of rods each of which also connects with one end of links in the preceding or following transverse row. In addition to interconnecting links to form a continuous surface the rods 32 also serve to connect the links 13 to chains of driving links which are located at points spaced transversely of the 15 grate. There is a driving chain at or near each edge and, if desired, other chains may be formed as described hereafter and provided at intermediate points also.

To form these chains drive links 34, 35 (Fig. 1) 20 are mounted parallel to each other in pairs and spaced laterally. Near each end thereof the links 34, 35 have transverse apertures 36 receiving hollow sleeves 37 for interconnecting the links of each pair, these links being secured to 25 the two sleeves by peening, welding or in other suitable manner. The pairs of drive links 34, 35 in a chain are spaced apart in alignment longitudinally of the grate as indicated at 34A, 35A and 34B, 35B, Fig. 8. Other drive links 40 30 extend between and join each successive pair of drive links to form an endless chain. Each link 40 is also transversely apertured near its end in order to loosely mount it on the sleeve at one end of a pair of links 34A, 35A and on the similar 35 sleeve at the adjacent end of the preceding or following pair of links 34B, 35B. The end portions of the links 40 lie intermediate the links 34, 35. The intermediate links 40 are loosely mounted on the sleeves 37 so as to accommodate 40 the canting of the links that occurs as the chain passes around the drive sprockets as illustrated in Fig. 2.

The chain may, if desired, be made up of longitudinally aligned links 34 fitted with laterally 45 projecting hollow sleeves 37 at each end and interconnected by links 40, the arrangement thus eliminating the other link 35 of each pair. However, the use of both links 34 and 35 is preferred since this results in a more substantial 50 construction.

The sleeves 37 are hollow for the purpose of receiving the rods 32 thereby supporting the grate links 13 that are carried on and interconnected by the rods. The drive links 34, 35 and 55 40 have lateral flanges 41 along one upper side edge. The flanges of the links 34, 40 face each other with the result that space is provided in which to mount a roller 42 on the sleeve 37 for engagement by the teeth of the sprockets 10, 11 60

in order to impart movement to the drive chain and grate links 13. The flange 41 on the link 35 faces the link 40 and overlies a hub or boss 43, which provides a more adequate bearing surface between the link 35 and the sleeve 37 than afforded by the thickness of the links.

In the form shown in Fig. 3 the intermediate link 40A has a hub portion 44 extending toward the outer link 34 and underlying the flanges 41 on links 34 and 40. The hub 44 also provides a large bearing surface between the link 40A and the sleeve 37. In this form the hub 44 also is engageable by the sprockets 10, 11 to drive the chain.

Fig. 5 shows two intermediate links 40B employed between a pair of drive links 34, 35 with the driving roller 42 beneath their opposed flanges 41. All drive links 34, 35, and 40B are loosely mounted on the sleeves 37 and held in place by nuts 45 threaded on the ends of the sleeves.

The construction shown in Fig. 6 includes a pair of parallel drive links 34, 35 and an intermediate link 40C as in Fig. 1, but here one drive link, as 35, is welded to the sleeve 37 while the other is held in place by a nut 45.

In all of the forms described above the drive links 34, 35 interconnected as pairs by sleeves 37 and the links 40, 40A etc. that joint successive pairs of drive links 34, 35 to form an endless chain all function as grate elements because they have fuel supporting surfaces 31 as do the grate links 13. However, in the form shown in Figs. 4 and 7 only the drive links 34, 35 are elements of the grate surface, the pairs of drive links 34, 35 being joined by strap links 46. Another difference in this form is that the pair of drive links 34, 35 lie closely adjacent each other and the strap links 46 leading to a preceding or following pair are on the outside of the assembly. The links 34, 35 and 46 are loosely mounted on the sleeve 37 and held in place by nuts 45. The grate links 13A immediately adjacent the drive chain have lateral flanges 48 along their upper side edges and facing the chain so as to overlie and protect the strap links 46 of the drive chain.

A drive chain is made up of a series of links that may be considered to be permanently connected together to form the endless driving chain. It will be recalled that the rods 32 carrying the grate links 13 are removably received in the hollow sleeves 37 forming part of the chains at or near the sides of the grate as illustrated in Figs. 8 and 9, or at an intermediate location as indicated in Figs. 6, 7, and 9. When several rods 32 are removed endwise and the grate links 13 through which these rods extended are taken out of the grate surface access may be had to parts of the stoker therebeneath. The remaining grate links 13 remain fully supported from the drive chains through the intermediary of the unremoved rods 32 extending into the related hollow sleeve 37 that forms part of the drive chains. Because the drive chains are not broken or opened up the rods 32 in which they have been taken out remain fully supported in the related sleeves 37 of the chain and consequently they continue to support grate links 13 through which they extend. The two rods 32 bordering the margin of the opening extend through an aperture 33 at one end of each grate link 13 of the two transverse rows immediately adjacent the opening; thus, these grate links are supported at one end and would swing down into the wind box, as illustrated in Figs. 1 and 2.

In Fig. 8 it is assumed that several transverse rows of grate links lying between the drive chains have been removed. In this figure the drive chains are assumed to be made up of drive links of the forms illustrated in Figs. 1, 2, or 6. Fig. 5 13 represents the removal of several rows of grate links when employing the drive link construction illustrated in Fig. 4.

This application is a division of that filed in my name under Serial No. 271,859 on May 5, 1939.

What I claim is:

1. In a travelling grate having at each of a plurality of points spaced transversely thereof a series of drive links arranged in spaced relation with their longitudinal axes disposed in the direction of grate movement and spaced apart in end to end relation, each link being formed near each end thereof with a transverse aperture; hollow sleeves fitted in said apertures of each link and extending from one side of the latter; other similarly disposed drive links formed near each end thereof with transverse apertures for fitting them on a sleeve at one end of one of said first drive links and on the sleeve at the adjacent end of a following or preceding first mentioned drive link for connecting all drive links of a series to form an endless chain; grate links arranged in side by side and end to end relation with their longitudinal axes disposed in the direction of grate movement between said chains of drive links to form a fuel supporting surface, each grate link being formed with longitudinally spaced apertures in alignment with like apertures of other grate links located laterally thereof; and rods extending through apertures in a plurality of laterally spaced grate links and extending through the apertured sleeves carried by drive links of said chain to support said grate links therefrom. 30

2. In a travelling grate; a plurality of links with their longitudinal axes disposed in the direction of grate movement and arranged in side by side and end to end relation to form a grate having air passages between the ends and sides of adjacent links, each link being formed with longitudinally spaced transverse apertures, means for interconnecting said links to form an endless fuel supporting surface comprising: a chain of drive links at each of a plurality of points spaced transversely of the grate, each chain comprising a number of links disposed with their longitudinal axes in the direction of grate movement and spaced apart in end to end relation, each link being formed near each end thereof with a transverse aperture; hollow sleeves fitted in the transverse apertures in said links and projecting from one side thereof; other similarly disposed drive links each formed near each end thereof with a transverse aperture for journaling it on a sleeve at one end of one of said first links and on the sleeve at the adjacent end of the next link of said chain for interconnecting said drive links in endless series; and transverse rods spaced longitudinally of the grate in accordance with the spacing of the apertures in said grate links and extending transversely of the grate through said apertures in a plurality of said grate links and into sleeves carried by drive links in several chains spaced transversely of the grate for supporting the plurality of grate links carried thereon from said drive links. 45

WILLIAM LLOYD.
